US0D1027186S

(12) **United States Design Patent** (10) Patent No.: **US D1,027,186 S**
(45) Date of Patent: ** May 14, 2024

(54) **DENTAL IMAGING ATTACHMENT FOR A SMARTPHONE**

(71) Applicant: **Align Technology, Inc.**, San Jose, CA (US)

(72) Inventors: **Shai Farkash**, Hod HaSharon (IL); **Yossef Y. Atiya**, Modin-Maccabim-Reut (IL); **Maayan Moshe**, Ramat HaSharon (IL)

(73) Assignee: **Align Technology, Inc.**, San Jose, CA (US)

(**) Term: **15 Years**

(21) Appl. No.: **29/827,196**

(22) Filed: **Feb. 17, 2022**

(51) LOC (14) Cl. **24-02**

(52) U.S. Cl.

USPC **D24/152**

(57) **CLAIM**

The ornamental design for a dental imaging attachment for a smartphone, as shown and described.

DESCRIPTION

FIG. 1 is a top perspective view of a dental imaging attachment for a smartphone in accordance with the present invention;

FIG. 2 is a bottom perspective view thereof;

FIG. 3 is another top perspective view thereof;

FIG. 4 is a front elevation view thereof;

FIG. 5 is a back elevation view thereof;

FIG. 6 is a top plan view thereof;

FIG. 7 is a bottom plan view thereof;

FIG. 8 is a right side elevation view thereof; and,

FIG. 9 is a left side elevation view thereof.
